US0D1100828S

(12) **United States Design Patent** (10) **Patent No.:** **US D1,100,828 S**
(45) **Date of Patent:** **** Nov. 4, 2025**

(54) **MOTOR**

(71) Applicant: **BRIGGS & STRATTON, LLC**,
Wauwatosa, WI (US)
(72) Inventor: **Nicholas Zeidler**, Brookfield, WI (US)
(73) Assignee: **Briggs & Stratton, LLC**, Wauwatosa,
WI (US)
(**) Term: **15 Years**
(21) Appl. No.: **29/905,333**
(22) Filed: **Oct. 19, 2023**

(51) LOC (15) Cl. **13-01**
(52) U.S. Cl.
USPC **D13/112**

(58) **Field of Classification Search**
USPC D13/112, 113, 114, 122, 184, 199;
D15/1, 5, 148, 149; D21/528, 561
CPC H02K 5/06; H02K 5/225; H02K 11/33;
H02K 9/14; H02K 7/1025; Y02T 10/72;
B60K 7/0007

(57) **CLAIM**

The ornamental design for a motor as shown and described.

DESCRIPTION

FIG. 1 is a top perspective view of the claimed design for a motor;

FIG. 2 is a bottom perspective view from below of the claimed design of FIG. 1;

FIG. 3 is a top view of the claimed design of FIG. 1;

FIG. 4 is a bottom view of the claimed design of FIG. 1;

FIG. 5 is a front view of the claimed design of FIG. 1;

FIG. 6 is a rear view of the claimed design of FIG. 1;

FIG. 7 is a left side view of the claimed design of FIG. 1; and,

FIG. 8 is a right side view of the claimed design of FIG. 1. Any portion of the article depicted in broken lines forms no part of the claimed design.

1 Claim, 8 Drawing Sheets
